BY ^{CHARLES} ^{WILSON}
ATTORNEY.

UNITED STATES PATENT OFFICE.

LEON S. BRACH, OF NEWARK, NEW JERSEY.

DESIGN FOR A TEMPERATURE-INDICATING DEVICE.

60,848.

Specification for Design.

Patented Apr. 18, 1922.

Application filed August 2, 1921. Serial No. 489,402. Term of patent 3½ years.

To all whom it may concern:

Be it known that I, LEON S. BRACH, residing at Newark, county of Essex, and State of New Jersey, have invented a certain new, original, and ornamental Design for a Temperature-Indicating Device, of which the following is a specification, reference being had to the accompanying drawing, forming part thereof.

Figure 1 is a front view; and
Figure 2 is a side view.

I claim:

The ornamental design for a temperature indicating device.

LEON S. BRACH.
